UNITED STATES PATENT OFFICE

EDWARD C. EKSTROMER, OF REDWOOD CITY, CALIFORNIA, ASSIGNOR OF ONE-HALF TO JAMES F. GALLAGHER, OF BERKELEY, CALIFORNIA, BLANCHE NASH GALLAGHER, EXECUTRIX OF SAID JAMES F. GALLAGHER, DECEASED; SAID EKSTROMER ASSIGNOR OF ONE-HALF TO THE EDWARD C. EKSTROMER CORPORATION, A CORPORATION OF NEVADA

PUMP AND DRIVING MECHANISM

Application filed May 21, 1930. Serial No. 454,300.

My present invention relates to oil well pumps and more particularly to a submersible unit of the short stroke type and a driving means therefor, which can be lowered 5 into a well upon the end of a discharge pipe.

An object of my invention is to provide a new, and efficient pump unit of novel design which can be lowered into a well upon the end of a discharge pipe.

10 A further object of my invention is to provide an oil well pump of the so called short stroke type which will produce a substantially uniform flow of oil when in operation at the bottom of a well.

15 Another object of my invention is to provide a new and novel driving means for my improved pump which is capable of converting a continuous rotary motion into a short stroke reciprocating motion.

20 A further object of my invention is to provide an arrangement of short stroke pumps which can be operated by a single driving means to produce a substantially uniform flow of oil.

25 Other objects and advantages of my invention will be in part evident and in part pointed out in the following description taken in connection with the accompanying drawings wherein I have illustrated a preferred form of my improvement.

At the present time oil well pumps of the reciprocating type are operated by means of a motive power unit located on the surface at the top of the well. These units comprise a prime mover, a walking beam which is oscillated by means of a pitman connected to the prime mover and a sucker rod which is attached to the walking beam and caused to move with a reciprocating movement as the walking beam is oscillated. The sucker rod extends downwardly into the well where it connects to the moving parts of the pump. The use of such a sucker rod is attendant with many undesirable features, some of which are: stretching, whipping, and its weight. All of these undesirable features become more exaggerated as the depth of the well increases and it is therefore desirable that some means be provided whereby these difficulties can be overcome.

In order to overcome these difficulties, I propose to construct a prime mover element for operating a reciprocating oil well pump of novel construction which can be lowered into the well and which will dispense with the use of the above referred to motive power unit and its cooperating sucker rod. The greatest obstacle in providing such a unit is in providing a unit small enough to be inserted into the well casing, which casing is of a relatively small diameter for such a purpose. This restriction in the size of such a unit, however, applies only to its horizontal or diametrical dimensions and since it can be made of almost any desired length, I propose to build a multiple pump device by employing a plurality of smaller pump units which as a whole is small enough to be inserted into the well. These smaller pump units are so disposed and connected with a common discharge conduit that when in operation they will produce a substantially uniform flow of oil to the discharge pipe.

As a driving means for my improved multiple pump unit, I propose to employ the arrangement of electric motors disclosed in my copending application, Serial Number 266,471, filed April 2, 1928. For the purpose of this description it may be said that the arrangement disclosed in the above application contemplates a plurality of fractional horse-power motors disposed end to end one above the other operating in tandem and of such a diameter that they may be contained in the usual oil well casing.

Between these motor units and the pump unit, I employ a power translating device of novel design which will convert the rotary movement of the motors to a short stroke reciprocating movement which is then applied to the driving or sucker rods of the individual units of the multiple pump device.

For a better understanding of my invention, reference should be had to the accompanying drawings, in which I have shown by way of illustration and not of limitation apparatus which represents the best embodiment of my device now known to me. I desire to have it understood, however, that many changes and modifications can be made

therein without departing from the spirit of my invention.

In these drawings—

Fig. 1 is a fragmentary vertical sectional view of the upper end of my improved multiple pump unit,

Fig. 2 is a view similar to Fig. 1, showing the middle portion of my pump unit,

Fig. 3 is a view similar to the above views taken along a plane in front of the center line, as along line III—III of Fig. 6, looking in the direction of arrows,

Fig. 4 is a fragmentary vertical sectional view taken along the center line of the power translating means,

Figs. 5 and 6 are horizontal sectional views taken respectively along lines V—V and VI—VI of Fig. 3,

Figs. 7, 8 and 9 are similar views taken respectively along lines VII—VII, VIII—VIII and IX—IX of Fig. 4,

Figs. 10, 11, 12 and 13 are horizontal sectional views taken along lines X—X, XI—XI, XII—XII and XIII—XIII of Fig. 3,

Fig. 14 is a sectional view taken along line XIV—XIV of Fig. 3,

Figs. 15, 16, 17, 18 and 19 are horizontal sectional views taken respectively along lines XV—XV, XVI—XVI, XVII—XVII, XVIII—XVIII and XIX—XIX of Fig. 1, and

Fig. 20 is a diagrammatic developed view illustrative of the arrangement and mode of operation of the multiple pump device and driving means.

In order to fully illustrate my invention I have prepared a large number of figures in the drawings, however, it is believed that an understanding of the invention will be facilitated and the description simplified if reference to the drawings is limited to the principal figures thereof. I shall therefore in explaining the apparatus limit my description to Figs. 1, 2, 3 and 4 and rely upon Fig. 20 to explain its mode of operation. Corresponding numerals will be applied to like parts in the other figures of the drawings and it is believed that with an occasional reference thereto an understanding of my invention will be complete.

In Figs. 1, 2, 3 and 4 of the drawings 10 designates an outer shell or casing of tubular construction. This casing 10 extends throughout the total length of my apparatus and is adapted to enclose both the pump units and the motor driving means. The upper end of the shell or casing 10 is provided with a cap 11 which is threaded to connect with the lower end of a discharge pipe not shown. It will be understood that this discharge pipe is in dimension and construction similar to standard practice in the oil fields at the present time, i. e. a pipe varying from 2" to 3" and over in diameter. Arranged within 15 and extending throughout the length of the

casing 10, I provide an inner casing 12 which is held in spaced relation with the casing 10 so as to provide an annular conduit 13 through which oil or any other liquid being pumped may flow. In order to provide an inlet for the oil to the conduit 13 the lower end of the outer casing 10 is provided with the usual screen button apertures 14 as shown in Figs. 3 and 4. The apertures extend completely to the lower end of the casing 10 which extends sufficiently far below the power translating means shown in Fig. 4, to enclose an arrangement of motors such as is illustrated in my above referred to copending patent application.

Disposed within the inner casing 12, I show a body member or support 15 having an axially extending central conduit 16 about which a plurality of short stroke pump units are arranged. These short stroke pump units, in this embodiment of my invention, are shown as formed by providing cylinders 17 which are disposed in the support 15 on opposite sides of the central conduit 16 and in which suitable pistons 18 having check valves 19 operate. Cooperating with the pistons 18 and the valves 19, the cylinders 17 have at their inlet ends check valves 20. The pistons 18 are cored out to provide passageways 21 for the liquid being pumped and at the bottom of the passageways 21 the pistons are slotted as at 22 to form a cage construction or outlet passageway which communicates with outlet ports 23 formed at these points in the central conduit 16. At the upper end of the central conduit 16 the body member 15 carries a suitable check valve 24 which serves to prevent a back flow of the liquid pumped and adjacent the inlet end of the cylinders 17 the body member is provided with cavities 25 that cooperate, as will hereinafter appear, to form a passageway for the liquid pumped. In the upper half of the body member or support 15 the short stroke pump units are shown as arranged in one plane on opposite sides of the central conduit 16 and in the lower half of this body member or support the pump units are shown as similarly disposed but in a plane at right angles to that in which the upper units are disposed.

The above assembly is arranged to be disposed within the inner shell 12 so that the cavities 25 will register with what I shall term inlet ports 26. These inlet ports 26 pass through the inner shell 12 and complete a passageway to the individual pump units, for the liquid pumped, through the screen buttons 14 and the annular conduit 13 formed between the outer and inner shells 10 and 12. After the pump assembly is thus placed in the inner shell 12 a collar 27 carrying a packing 28 is secured thereon to hold the parts in proper relation and seal the annular conduit 13. A tubular coupling 29 is then se-

cured over the central conduit 16 to connect it with a conduit 30 formed in the cap member 11. This tubular coupling 29 also carries a packing 31 to facilitate the assembly and 5 maintain a liquid tight connection.

By referring now particularly to Figs. 3 and 4, it will be seen that each of the pistons 18 are provided with crossheads 32 to which parallel extending piston rods 33 connect.

10 The lower piston rods are shown in Fig. 4, as connected to oppositely disposed reciprocatable members 34, each of which carry a roller or cam rider 35 and the upper piston rods 33 (shown dotted in Fig. 2) are connected to similar but longer members 36 which carry rollers or cam riders 37. These roller carrying members 34 and 36 are each provided with downwardly projecting tongues 38 which slide in grooves 39 formed

20 in the outer surface of a bearing housing 40. Above the bearing housing 40 and engaged by the rollers or riders 35 and 37, I provide a cylindrical cam member 41 in which the cam effect is produced by a pair of angular-

25 ly disposed grooves 42 extending completely around the cylinder. This cylinder 41 is mounted to rotate freely upon suitable bearings 43 and 44 and has a downwardly extending shaft 45 to which any suitable motive power may be applied. In the present instance it is contemplated as previously suggested that a power unit of the type disclosed in my copending application will be used.

30 In order to provide an electric current supply for the electric motors, should such a motive power means be employed, I show the cap member 11 as having a suitable conduit outlet through which the electric current conduits may pass. In Fig. 1 this outlet is designated by the numeral 46 and is shown as having a three wire cable 47 passing therethrough. The cable 47 extends downwardly through the collar 27 and from this point three individual conductors 48 pass through 45 an opening 49 in the inner shell 12 and extend downwardly there along to the motors. The cables 48 are protected from the oil and mechanical damage by the provision of a channel forming member 50 which is welded to the inner shell 12.

50 It is believed that with the above description and reference to the several horizontal sectional views that a clear understanding of the construction and arrangement of parts will be had. I shall therefore, now proceed with a description of the operation of the apparatus.

55 It will be assumed that the unit has been connected with a suitable driving means such as the motor units referred to and has been lowered into an oil well upon the end of a suitable discharge pipe and that the motors have been energized. Under these conditions the cylindrical cam member 41 will be 60 rotating continuously in one direction. This

will cause the cam riders 35 and 37, by reason of their engagement with the grooves 42, to move up and down and impart a reciprocating movement to the piston rods 33 which movement will in turn be transmitted to the pistons 18 and thus produce a pumping action in the cylinders 17.

65 By referring to Fig. 20 of the drawings, which as previously stated is a developed schematic diagram, showing the relative positions of the parts, it will be seen that there are twelve of these cylinders 17 with cooperating pistons 18. These cylinders and pistons are also clearly disclosed as arranged in four groups of three cylinders each which 70 groups I shall designate, from left to right, by the letters A, B, C and D. Upon inspection of any particular group it will be seen that the arrangement of the valves and disposition of the cylinders 17 are such that at 75 least one piston of each group will be operating on the pumping stroke at all times while the pumping device is in operation.

80 With particular reference to Fig. 20 of the drawings, and assuming that the cylindrical member 41 with the grooves 42 is moving to the left, it will be seen that the rollers 35 and 37 will move up or down as indicated by the arrows adjacent the corresponding rods 33. At the instant illustrated 85 the pistons 18 of group A are shown as moving downwardly while the pistons of the oppositely disposed group C are moving upwardly. Under these conditions the middle piston of group A will be pumping and 90 the end pistons will be sucking, while in the opposite group C the middle piston will be sucking and the end pistons will be pumping.

95 As a result of this arrangement it will be readily seen that the difference in the load 100 upon each side of the cam cylinder 41 is reduced to a minimum. What has been said with respect to groups A and C in the lower part of the device, is also true of groups B and D located in the upper part of the device. 105 At the instant illustrated, the parts of the latter groups may be said to be on a dead center but at an instant later, the end pistons 18 of group B will be pumping and the middle piston will be sucking and in group D 110 the middle piston will be pumping and the end pistons will be sucking.

115 As the pistons 17 operate on their pumping stroke the oil pumped will be forced through the ports 23 and into the central 120 conduit 16 and thence to the discharge pipe and out of the well. When any two of the groups of pistons are on their so-called dead center the other two groups of pistons will be at mid stroke and as a result a substantially 125 uniform flow of oil will result. This feature is not only important with respect to the flow of oil but is also advantageous as it imposes a substantially uniform load upon the driving means, and as a result the maximum 130

rating of the driving equipment need be of no greater power than the average power requirements.

While I have, for the sake of clearness and in order to disclose my invention so that the same can be readily understood, described and illustrated specific devices and arrangements, I desire to have it understood that this invention is not limited to the specific form disclosed but may be embodied in other ways that will suggest themselves, in view of this broad disclosure, to persons skilled in the art. It is believed that this invention is broadly new and it is desired to claim it as such so that all changes as come within the scope of the appended claims are to be considered as part of this invention.

Having thus described my invention, what I claim and desire to secure by Letters Patent is—

1. In a short stroke pump device the combination of, an elongated member having a central conduit extending axially therethrough and having a plurality of pump cylinders adjacent to and communicating with said conduit, a sleeve surrounding said member having ports communicating with said pump cylinders, pump pistons in said cylinders, check valves cooperating with said pistons and cylinders, and means for imparting a reciprocating movement to said pistons.

2. A submersible pump for oil wells and the like comprising, an elongated support having a central discharge port extending axially therethrough, a plurality of pump units arranged axially along and concentrically about said central discharge port, a sleeve surrounding said support having inlet ports communicating with each of said pump units, and means below said pump units and within said sleeve for driving the pump units with a reciprocating movement.

3. A short stroke pump unit comprising, a plurality of pump cylinders arranged in alignment in a cylindrical housing and capable of being lowered into a well, a plurality of pistons cooperating with said cylinders, driving rods for said pistons extending through said housing adjacent the cylinders, a rotatable cylinder having a pair of continuous cam trackways extending there around, and means connected with said driving rods engaging said cam trackways adapted to impart a reciprocating motion to the driving rods and pistons as said cylinder is rotated about an axis extending parallel with the axis of the pump cylinders.

4. A short stroke pump for oil wells and the like comprising, a member having a central conduit, a plurality of pump cylinders arranged along and about said central conduit, two circular cam trackways disposed below said pump cylinders adapted to rotate about an axis extending through said central

conduit, pistons in said pump cylinders, means below said cam trackway for driving the latter continuously with a rotary movement, and means disposed about said central conduit connected with said pistons and engaging said cam trackways adapted to alternately impart a pumping movement to said pistons as said circular cam trackway is rotated continuously in one direction.

5. A short stroke pump unit comprising, a plurality of pump cylinders arranged in axial alignment in a cylindrical housing and capable of being lowered into a well, a plurality of pistons cooperating with said cylinders, driving rods for said pistons extending through said housing on opposite sides of the cylinders, a rotatable cylinder having two continuous cam grooves extending there around, and means connected with said driving rods engaging said cam grooves adapted to impart a reciprocating motion to the driving rods and pistons as said cylinder is rotated about an axis extending parallel with the axis of said pump cylinders, said last means being disposed around the cylinder housing and alternately in different cam grooves so that each groove will have a connecting means on opposite sides thereof substantially as described.

6. In a pump of the character described, the combination of a central body member having an oil discharge passageway extending therethrough, a pair of oppositely disposed pump cylinders arranged adjacent said passageway and communicating therewith, a second pair of oppositely disposed pump cylinders arranged at another point along said central conduit and displaced at an angle from said first pair of cylinders, pistons within said cylinders, a circular cam trackway arranged below said cylinders, and means for engaging said cam trackway adapted to drive said pistons of each pair of cylinders in opposite directions, whereby as said pistons operate a substantially continuous flow of oil will be pumped into said discharge passageway.

EDWARD C. EKSTROMER.
